GAME APPARATUS

Michael E. Minger, Pottsville, Pa., assignor of one-half to Edward P. White, Pottsville, Pa.

Application December 20, 1938, Serial No. 246,888

1 Claim. (Cl. 273—85)

This invention relates to aerial projectile game apparatus, and its general object is to provide an apparatus of that character in the form of a toy which I term table basketball, in that it includes a suspended basket and a manually operated and controlled catapult for projecting a ball toward the basket, as well as chance means actuated by the ball when passed through the basket, to determine the score of the players, with the result it will be seen that my game combines the elements of skill and luck and therefore affords much amusement and fun, regardless of the skill of the players.

A further object is to provide a toy basketball game apparatus that is simple in construction, inexpensive to manufacture and extremely efficient in operation, use and service.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a vertical sectional view taken through the apparatus which forms the subject matter of the present invention with parts in elevation.

Figure 2 is a top plan view thereof.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a view illustrating the indicia on the respective faces of the cube or die used with my game.

Figure 6 is a fragmentary top plan view of a modified form of catapult.

Figure 7 is a vertical sectional view taken therethrough.

Referring to the drawings in detail, the reference numeral 1 indicates the base of my apparatus which as shown is of flat elongated rectangular formation and secured to the base preferably midway its ends for disposal transversely thereof is a strip member 2 recessed to receive the base and of a length to extend beyond the opposite sides thereof to aid in supporting the same against tilting or undue movement, as

will be apparent upon inspection of Figures 2 and 4.

The basket supporting means is arranged at one end of the base 1 and includes a cross member 3 fixed to the base by a wing nut and bolt connection 4 and recessed as shown to fit the base and to extend upon opposite sides thereof, to cooperate with the strip member 2 for the purpose set forth for the latter. Secured to and rising from the extending ends of the cross member 3, is a pair of parallel uprights 5 having secured thereto adjacent their upper ends in bridging relation, a bank board 6.

The basket includes a wire frame 7 having a ring like portion from which extend fastening bracket members 8 passed through the board and disposed in clamping engagement therewith, as best shown in Figure 1, and threaded on the ring like portion is the body 9 of the basket which is preferably formed from woven cord in the usual truncated conical formation.

Mounted adjacent the opposite ends of the base 1 is the catapult or ball projecting means of my apparatus, and in the form as shown in Figures 1 and 2, the catapult includes a mounting block 10 disposed transversely of the base and secured thereto by lugs 11 fixed to the opposite sides of the base, as indicated in Figure 1. The lugs have openings therein adjacent their upper ends to act as bearings for the ends of a pivot pin 12 that extends transversely through one end of the flat or paddle like catapult lever 13 which has mounted on the upper surface thereof adjacent its opposite end and secured accordingly by adhesive material or any suitable means, 35 a ball cup 14 having a concaved seat therein for receiving the ball 15.

The catapult is spring actuated and limited in its swinging movement by toggle links 16 arranged in pairs and having their outer ends 40 pivotally connected to the lever 13 and the base respectively, while their inner ends are pivotally connected to the ends of a pin 17 which has secured thereto one end of a coil spring 18, the opposite end of the spring being connected to an 45 eye-bolt 19 mounted through the block 10 and provided with a wing nut 20. By that construction, it will be obvious that the throw of the lever 13 can be adjusted so as to retain the catapult under proper tension at all times, so that it will 50 have sufficient power to project the ball a sufficient distance to pass through the basket.

Secured to the base and disposed transversely thereof adjacent to the basket supporting means is a mounting block 21 reduced throughout its 55

length at its upper portion to act as a support for a paddle like platform 22 to rest thereon for rocking movement. However, the platform or rocking member 22 may be rockably secured to the mounting block 21, but in any event one end portion of the rocking member 22 is arranged below the basket for disposal in the path of the ball when passed therethrough, as shown by the arrows in Figure 1, so as to rock the member 22 from its full line position to its dotted line position, for projecting a die or cube 23 from the opposite end thereof, as likewise shown in Figure 1, the cube having playing indicia on the respective faces thereof, as clearly shown in Figure 5, for keeping the score of the game and indicating plays. It will be understood that when the cube comes to rest after being projected, that the indicia on the upper face thereof is used for scoring and playing purposes.

20 In Figures 6 and 7 I have illustrated a modified form of catapult which includes a flat spring arm or lever 24 secured to the base 1 by a wing nut and bolt connection 25 and supported at an inclination with respect to the base by a mounting block 26, the latter having an inclined upper surface for that purpose. Secured adjacent the upper end of the lever 24 by a wing nut and bolt connection 27 is a ball cup 28.

It will be obvious that regardless of the form 30 of catapult used, that the ball is placed within the cup thereof, thence pressure is applied to the

free end of the lever by the player and when the pressure is released, the ball will be projected into space toward the basket, the object being to cause the ball to pass through the basket for actuating the chance means, that includes the 5 indicia bearing cube, in the manner as previously set forth.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

In a table basketball game, a base, a basket suspended above said base, a supporting block secured to said base and having a reduced upper portion providing a bearing, a platform rockably mounted on the bearing and arranged with one end portion thereof directly underlying the basket for disposal in the path of a ball when passed through the basket for the ball to tilt the platform, and playing and score keeping indicia bearing means to be placed upon the opposite end portion of the platform to be projected therefrom when the platform is tilted by the ball, so as to determine the plays and score of the game when said means comes to rest.

MICHAEL E. MINGER.
